UNITED STATES PATENT OFFICE.

GARABED G. HEGHINIAN, OF NEW YORK, N. Y.

COIN-CONTROLLED VENDING MACHINE.

1,095,630.

Specification of Letters Patent.

Patented May 5, 1914.

Application filed November 9, 1911. Serial No. 659,327.

To all whom it may concern:

Be it known that I, GARABED G. HEGHINIAN, of the city of New York, in the county of Kings and State of New York, have invented certain new and useful Improvements in Coin-Controlled Vending-Machines; and I do hereby declare the following to be a full, clear, and exact description of the invention, such as will enable others skilled in the art to which it appertains to make and use the same.

My object is to provide an improved coin controlled vending machine especially adapted for use in theaters, street cars and other public places and conveyances.

My invention relates to that class in which each merchandise receptacle contains only a single piece or package of merchandise but I provide a plurality of such receptacles within one housing or casing, each of the receptacles having a door and releasing mechanism, the latter under control of coin actuated means common to all the receptacles.

In the drawings, Figure 1 is an elevation partly broken away. Fig. 2 is a top view. Fig. 3 is a section on line *x*—*y* Fig. 2. Fig. 4 is a perspective. Fig. 5 is a modified form. Fig. 6 shows the door covering the coin receptacle. Fig. 7 is a vertical sectional view of the form shown in Fig. 5. Fig. 8 is an edge view of the door of Fig. 6 and Fig. 9 shows one of the chute latches.

Referring to the drawing, the casing is divided interiorly into four compartments 1, 2, 3, 4. Each of these compartments is provided with a door 6 and a spring 7. The merchandise lies between the spring and the door so that when the later is released the spring forces the door open and ejects the package. The doors have latch plates 8, 9, 10, 12, respectively engaged by levers 13, 14, 15, 16 which are held in engagement with their co-acting latch plates by springs 17, 18. I have shown the spring 17 connected to levers 13 and 14, and spring 18 connected to levers 15 and 16 as that is an appropriate arrangement in the construction illustrated. The long arms 19, 20, 21, 22 of the several levers extend toward the center of the casing. Each of the compartments has a corresponding coin chute leading from the top of the casing and indicated at 1', 2', 3', 4'. These chutes are provided with latches 23 at the point of insertion of a coin.

55 B is a partition between chutes 2', 3'.

As shown in Figs. 2 and 4, the coin chutes

2', 3' of the lower receptacles 2, 3, are out of alignment with chutes 1', 4', of the upper receptacles 1, 4. A shaft 25 is mounted in the casing and provided with a hand wheel 30. Keyed to this shaft are two coin carriers comprising disks or wheels 26 and 27, the former in line with the coin chutes 2', 3' of receptacles 2 and 3, and wheel 27 in line with the coin chutes 1', 4', of receptacles 1 and 4. 60 Each of the parts 26 and 27 is formed with a recess 28 in its periphery adapted to receive a coin of prescribed denomination. The long arms 19, 20, etc., of the levers have their extremities close to their respective 65 wheels 26, 27. In the position of the parts shown in Fig. 1 a coin has passed into the slot 1' of compartment 1 and the operator has turned the hand wheel 30 until the recess 28 of wheel 27 has received the coin. On 70 further turning the hand wheel the coin becomes a positive factor in acting directly upon the arm 19 of lever 13 of compartment 1. Wall A prevents the disk being turned 75 the wrong way. This turns the lever on its fulcrum and disengages it from the latch plate 8, allowing the door of compartment 1 to swing open and the merchandise to be ejected under the tension of spring 7. The coin then falls to the bottom of the casing 80 into a receptacle 31 which is shown separated by a partition 32 (Fig. 3) from the merchandise receptacles. Suitable inscription on the top of the casing indicates to the patron the coin chute in which to insert the 85 money in order to receive the desired merchandise. In order to obtain the contents of compartment 4 the hand wheel 30 is turned in the opposite direction. The contents of compartments 2 and 3 may be obtained in 90 the same manner provided the proper coin chutes 2', 3' are employed. This calls the wheel 26 into action, the lever arms 20, 21 with which it co-acts being indicated in dotted lines in Fig. 1. The levers of compartments 2 and 3 are shown formed with an 95 angular extremity in order that the pressure of the coins upon them may swing them in the desired direction. The construction thus far described is adapted for attachment to 100 seats in theaters and other stationary objects. I also make provision for the use of the invention on car seats which are inverted in changing the direction of the seats and the modifications necessary for this purpose 105 are illustrated on Sheet 2 of the drawings. 110

As shown in Fig. 5 the casing is provided

with chutes at both its upper and lower ends. The chutes indicated at 40, 41, 42, 43 are for the operation of levers 50 and 53. Thus chutes 40 and 41 are continuations of chutes 42 and 43. Also I have shown the chutes 44, 45 which conduct coins to levers 51, 52, extending entirely through the casing and as out of alignment with the chutes 40, 41 as previously described in the preferred form of embodiment. These chutes are separated by a wall 66. The shaft 46 carries a hand wheel 47 and two disks 48, 49, disk 48 being in alignment with chutes 40, 41, 42, 43, and disk 49 in alignment with chutes 44, 45. The levers 50, 51, 52, and 53 co-act wth a coin which has been received by one of the disks in the manner previously described, wall 65 preventing rotation of the disk in the wrong direction. As shown in Fig. 7 a partition 55 separates the merchandise compartments from the coin receptacle 56. This coin receptacle has a door or cover 57 which may be formed with a flange at its upper end 58 passing beneath the outer wall 59 of the casing as shown in Fig. 7. At its lower end the closure has a locking device 60. The extremities of coin chutes 42, 43 are formed with guiding surfaces 61, 62 tending to deflect coins into the receptacle 56. When the portion of the casing at which the coin receptacle is shown is at the top, as when the device is affixed to a car seat, a coin inserted through chute 42, after co-acting with lever 50 will pass downward through the chute 40, but will be retained there by the latch 63.

I claim as my invention:—

1. In a vending machine, the combination with a casing provided with a plurality of merchandise receptacles, each having a door, and a plurality of coin chutes each corresponding to one of said receptacles, of a coin disk formed with a recess to receive the coin from any one of said chutes, a latch lever for locking the door of each of said receptacles, means for rotating said coin disk to cause the coin to engage the latch lever to unlock the door of the receptacle corresponding to the chute through which the coin is introduced to the disk.

2. In a vending machine the combination with a casing provided with a plurality of merchandise receptacles, each having a door, and a plurality of coin chutes each corresponding to one of said receptacles, of a coin carrier to receive the coin from any one of said chutes, a latch lever for locking the door of each of said receptacles, means for actuating said coin carrier to cause the coin to engage the latch lever to unlock the door of the receptacle corresponding to the chute through which the coin is introduced to said

carrier and means preventing the coin engaging any of said levers except the one associated with the chute through which the coin is introduced.

3. In a vending machine, the combination with a casing provided with a plurality of merchandise receptacles each having a door, and a plurality of coin chutes each corresponding to one of said receptacles, of a disk provided with a recess to receive the coin from any one of said chutes, a latch lever for locking the door of each of said receptacles, means for rotating said disk to cause the coin to engage the latch lever to unlock the door of the receptacle corresponding to the chute through which the coin is introduced to the disk.

4. In a vending machine, the combination with a casing provided with a plurality of merchandise receptacles, each having a door, and a plurality of coin chutes each corresponding to one of said receptacles, of a coin carrier to receive the coin from any one of said chutes, a latch lever for locking the door of each of said receptacles, means for actuating said coin carrier to cause the coin to engage the latch lever to unlock the door of the receptacle corresponding to the chute through which the coin is introduced to said carrier, and a stop adapted to be engaged by the coin to prevent the coin engaging any of said levers except the one associated with the chute through which the coin is introduced.

5. In a vending machine, a pair of rotary disks each having a recess adapted to receive a coin, a pair of coin chutes in alignment with each of said disks, a pair of levers co-acting with a coin carried by one of said disks and controlling the closures of upper merchandise receptacles, a pair of levers co-acting with a coin carried by the other of said disks and controlling the closures of lower merchandise receptacles, and means for rotating each of said disks to operate one or the other of its respective levers.

6. In a vending machine, the combination with the two pairs of levers out of vertical alignment with each other and controlling the closures of four merchandise receptacles, a spring connecting a lever of one pair with the adjacent lever of another pair, a rotary disk in alignment with each pair of levers, a pair of coin chutes in alignment with each disk, and means for rotating said disks.

In testimony whereof, I have signed this specification in the presence of two subscribing witnesses.

GARABED G. HEGHINIAN.
